(57) **CLAIM**

The ornamental design for a compact nozzle tip cutter, as shown and described.

DESCRIPTION

FIG. 1 is a top perspective view of a compact tip cutter that incorporates a nozzle;

FIG. 2 is a bottom perspective FIG. 1;

FIG. 3 is a top plan view thereof;

FIG. 4 is a bottom plan view thereof;

FIG. 5 is a front elevation view thereof;

FIG. 6 is a left side elevation view thereof;

FIG. 7 is a right side elevation view thereof; and

FIG. 8 is a top perspective view of a second embodiment of a compact tip cutter; and,

FIG. 9 is a bottom perspective view of FIG. 8.
